UNITED STATES PATENT OFFICE.

JOSEPH M. BATTIN, JR., OF NEWARK, NEW JERSEY, ASSIGNOR OF ONE-HALF TO WILLIAM A. HUFF, OF SAME PLACE.

LUBRICATOR.

SPECIFICATION forming part of Letters Patent No. 279,120, dated June 12, 1883.

Application filed September 30, 1882. (No model.)

To all whom it may concern:

Be it known that I, JOSEPH M. BATTIN, JR., a citizen of the United States, residing in the city of Newark, Essex county, New Jersey, have invented certain new and useful Improvements in Lubricators, fully described and represented in the following specification and the accompanying drawings, forming a part of the same.

10 This invention consists in an improved construction, herein shown and described, for that class of lubricators adapted to operate under a pressure of steam and to feed a regulated amount of oil into any steam-receptacle.

15 The construction will be understood from the annexed drawings, in which Figure 1 is a central vertical section of a lubricator provided with my improvements. Fig. 2 is a detached view of the main stem or conducting tube. Fig. 3 is a section of the same just above the oil-outlet *d*. Fig. 4 is a section of the same at the center of the transverse oil passage or outlet *d*; Fig. 5, an end view, and Fig. 6 an edge view, of the guide-plug; and Fig. 7 is a detached view of the glass tube. The section shown in Fig. 1 is taken in a plane with the oil-outlet shown at *d* in Fig. 2, and the stem in the latter figure is viewed ninety degrees from the position shown in Fig. 1.

20 The construction is intended to obviate the use of crooked connections for the oil and steam passages, which are very liable to become fouled with the hot oil, and to secure a form for every part, so that it could be finished in the turning-lathe and the cost thereby reduced. These objects are secured by mounting the receptacle *A* upon a central stem, *B*, *C*, the part *B* extending below the part *A*, and the part *C* entering the receptacle or oil-cup *A* and reaching nearly to the top. The parts *B* and *C* will be termed "stems *B*" and "*C*" when referred to separately herein, while the whole stem will be called "stem *B C*." The stem *B* is made a little larger than the stem *C* to secure a shoulder, *s*, and a tight joint at the bottom of the cup *A*, into which it is screwed, and is provided with a threaded bore, *D*, at the point where it enters the cup, into which bore is fitted a screw-plug, *E*, constructed to

25 introduce the steam into the cup and to conduct the oil therefrom by passages readily ac-
cessible from the top of the cup when the cover *F* is removed. The latter is constructed with a packing, *t*, to close steam-tight, in the usual manner, and with a wooden knob, *u*, at 55 the top, as in many similar cups.
30 The stem *B* is provided with a removable screw-coupling, *G*, at the bottom, and is made hollow for the introduction of a glass tube, *H*, which is fitted to compressible packings *b* at 60 each end to be clamped steam-tight when the coupling upon the lower end of the stem is screwed up close. The stem *B* is also provided with holes *I* for viewing the interior of the glass tube.

35 The construction of the plug *E* is shown in Figs. 5 and 6, and consists in a threaded cylinder flattened upon two sides, and having a transverse opening, *c*, arranged to intersect a central bore, *e*, extending through the whole 70 plug and provided with a screw-thread to fit an internal valve.

40 The valve *a* is shown in Fig. 1, and consists in a screw-rod arranged to stand across the transverse opening *c* when turned around 75 by a head projecting above the upper end of the stem *C*. The upper end of the screw-rod *a* is shown provided with a hollow metallic cap, *J*, adapted to cover or shield the vertical passage in the top of the stem *C*, and thus prevent the introduction of oil or foreign substances into the passages *f*, formed by the flat places on the plug *E*, between the latter and the threaded bore of the stems *B* and *C*.
45 The cap may be roughened on the outside, 85 if needed, as it serves for the turning-head of the valve *a*.

45 The passages *f* are shown in Fig. 4, which shows the coincidence of the transverse opening in the plug at *c* with two holes, *d d*, formed 90 in the sides of the stem *C* at a level with the bottom of the oil-cup *A*. The transverse opening *c* is made parallel with the flat sides of the plug, and thus secures a connection between the interior of the plug at *e* and the oil in the 95 cup *A*, which is thus able to flow out of the cup at *e*, as indicated by the arrow *e'*. The flat sides being formed on the outside of the plug at ninety degrees from the openings *c*, the passages *f* have no connection with the latter, 100 but connect the bore of the glass tube *H* with the bore of the stem *C* by straight vertical

apertures, easily cleaned if obstructed by dirt. By the removal of the valve-stem *a* when the cover *F* is removed, the central bore, *e*, may be similarly cleaned.

5 The operation of my device is as follows: The cap *F* being removed, the cup *A* is filled with the lubricating-fluid, the valve *a* being screwed down to close the transverse opening *c*, and the cap *J* preventing the falling of oil 10 into the inside of the stem *C*. The valve *a* is then adjusted to permit a regulated escape of oil to flow out of the bore *e* by its gravity when hot, and its head *J* may be marked in agreement with some mark upon the mouth of the 15 cup *A*, to indicate the best position of the valve when adjusted by experiment. The whole lubricator is of course cut off from the steam pipe or chest which it is intended to lubricate, while being filled, by a suitable cock 20 or stop below the coupling *G*, and as soon as the stop is opened the steam is admitted to the bore of the glass tube, whence it passes above the oil through the passages *f* and the interior 25 of the stem *C* and the aperture between the top of the same and the cap *J*, as at arrows *J'*. The pressure thus produced upon the top of the oil, which is of course equal to the pressure in the steam-vessel to which the lubricator is attached, 30 is balanced by the entrance of steam into the bore of the plug at *e*, whence it presses upon the oil through the openings *c*. These openings being reduced to narrow slits by the valve *a* when the apparatus is in practical use, the steam has no tendency to enter therein, because opposed by a precisely equal pressure operating upon the top of the oil, and the latter is therefore at liberty to descend through the bore *e* at the natural rate induced by its weight. The passage of the oil is easily perceived as it 35 drops from the lower end of the plug *E*, which is extended into the glass tube opposite the openings *I* for that purpose, and the flow regulated by turning the head *J* when the cock in the connecting-pipe is closed and the cover *F* 40 removed.

I am aware that lubricators have been devised in which the regulating-valve could be operated without removing the cover of the apparatus, and in which the flow of the oil 45 could be distinctly observed by its passage up-

ward through a column of water; but the object of my invention has been to combine the greatest simplicity of construction with facility for cleaning and freedom from derangement. By my construction no water is used 55 to observe the flow of the oil, and all water condensed in the receptacle *A* would immediately sink to the bottom of the same and work out through the apertures *c* and *e*. The construction is therefore perfectly drained, 60 and not liable to freeze up when left at night, and is adapted to work in situations where the steam does not operate under the pressure referred to above. The plug *E* is referred to herein as made apart from the stem *B C*, and 65 such construction is the most convenient in practice; but it is obvious that if the same were cast in one piece with the stem, holes could be cored or drilled in place of the passages *f*, and that the holes or transverse openings *c* 70 could both be produced at the same time by drilling across the stem at the proper point.

Having thus described my invention, I claim the same in the following manner:

1. The combination of the cup *A* with the 75 central stem, *B C*, having a single opening at the bottom and provided with the holes *d*, and with the plug *E*, constructed with holes *c*, *c* and *e*, and arranged to form passages *f* inside the stem *C*, the whole substantially as 80 shown, and for the purpose set forth.

2. The combination, with the plug *E*, having holes *c*, *c* and *e* and flattened sides, of the stem *B C*, cup *A*, and screw-rod and valve *a*, provided with turning-head, substantially as 85 shown and described.

3. The combination, with the stem *B C* and the plug *E*, constructed and operating with the cup *A*, as described, of the screw-rod *a* and turning head or cap *J*, arranged to cover the 90 mouth of stem *C*, as and for the purpose set forth.

In testimony whereof I have hereunto set my hand in the presence of two subscribing witnesses.

JOSEPH M. BATTIN, JR.
